UNITED STATES PATENT OFFICE

160,842

AIRPLANE

Vincent J. Burnelli, Great Neck, N. Y.

Application July 14, 1949, Serial No. 3,906

Term of patent 14 years

(Cl. D71—1)

To all whom it may concern:

Be it known that I, Vincent J. Burnelli, a citizen of the United States of America, residing at Great Neck, in the county of Nassau, State of New York, have invented a new, original, and ornamental Design for an Airplane, of which the following is a specification, reference being had to the accompanying drawing, forming part thereof.

Fig. 1 is a top plan view of an airplane, showing my new design.

Fig. 2 is front view in elevation of an airplane.

Fig. 3 is a side view in elevation of an airplane.

Fig. 4 is a bottom plan view of an airplane.

I claim:

The ornamental design for an airplane, as shown.

VINCENT J. BURNELLI.
